CRANK CASE VENTING MEANS FOR PNEUMATIC TOOLS

Filed Nov. 8, 1923

UNITED STATES PATENT OFFICE

AXEL LEVEDAHL AND REINHOLD A. NORLING, OF AURORA, ILLINOIS, ASSIGNEES TO
INDEPENDENT PNEUMATIC TOOL COMPANY, OF CHICAGO, ILLINOIS, A CORPORA-
TION OF DELAWARE

CRANK-CASE-VENTING MEANS FOR PNEUMATIC TOOLS

Application filed November 8, 1923. Serial No. 673,471.

This invention relates to air venting means for crank cases of piston actuated portable pneumatic drills and like tools.

In general, our invention has reference to 5 an air venting means operated through centrifugal forces set up on rotating the crank shaft as described and claimed in our co-pending applications Serial Nos. 673,469 and 673,470, both filed November 8, 1923.

10 Our present invention has particular reference to a form of air venting means operating on that principle but applicable to tools of sizes smaller than the ones shown and described in our said copending applications, 15 and more specifically to tools having detachable counterweights made necessary by the removal of the crank shafts to free the connecting rods, as in the pending application of Iver A. Hanssen, filed December 18, 1922, 20 Serial No. 607,498.

Our invention consists further in the matters hereinafter described and more particularly set forth in the appended claims.

In the accompanying drawings—

25 Fig. 1 is a side view of a tool of the character described having incorporated therein an air venting means of our invention;

Fig. 2 is an enlarged vertical sectional view through said means and associated parts of 30 the tool; and

Fig. 3 is a bottom plan view of the counterweight and showing the associated parts of the air venting structure.

As shown in Fig. 1, the tool to which our 35 invention particularly relates has an outside case or housing 1 provided on one side with a combined handle and throttle 2, through which compressed air or other motive fluid is admitted to the tool for operating the same.

40 At the upper end of the case, the tool has a handle 3 of the loop or closed grip type. On the other side of the case is the spindle 4 carrying a twist drill 5, as shown. This type of tool is provided with a pair of cylinders 45 6, 6 on each side, only one pair being shown in the drawings. The cylinders are given a V arrangement and in them work single-acting pistons 7 connected by connecting rods 8 with the crank shaft 9.

50 The upper end 10 of the crank shaft 9 is

journaled in an antifriction ball bearing 11 in the adjacent end block or member 12 closing such end of the crank case 1. This end journal 10 is provided with a bore or passage 13 drilled into the same from the outer end 55 of the journal. On the crank shaft 9 at the end journal 10 is a counterweight 14. This is removably connected with the crank shaft at the end journal 10 in accordance with the disclosure made in said Hanssen application, 60 Serial No. 607,498. Removability of the counterweight 14 is made necessary by reason of the one-piece bearing sleeves or members 15, 15 carried by the connecting rods 8.

The bore 13 opens at its outer end into an air receiving chamber 16 formed above the same in the closure 12. This chamber 16 finds outlet to the atmosphere through a series of outlet ports 17 drilled or otherwise formed in the same. Extending into the bore 13 from the chamber 16 is a stationary tube 18 carried at its upper end by a cup 19 having a central portion forming the bottom wall of the chamber 16 and its side portions annular and 70 engaging against the end block 12. 75

The counterweight 14 is provided with one or more passages 20 arranged at an angle to the bore 13 and opening at their inner ends into the same through connecting ports 21 formed in the end journal 10. These passages 20 open at their outer ends into enlarged chambers 22 formed in the counterweight 14, as shown. Each chamber 22 has a restricted inner portion 23 forming a seat for a ball valve 24, which when open rests 80 against a stop pin 25 carried by the counterweight 14 in the associated end chamber 22, as shown in Fig. 2. 85

In use, the drill may be held in various working positions, depending on the lay of the work. When the drill is held in the position shown in Figs. 1 and 2, the end journal 10 is uppermost and the drill bit 5 and the passage 20 both extend downward with the stop pin 25 below the ball valve 24. In this position, when the drill is idle, the ball valve 24 will automatically unseat and come to rest against the stop pin 25 by the force of gravity. When the drill is operated in this position, centrifugal forces which are set 90 95 100

up by the rotation of the crank shaft 9 will also co-operate to retain the valve 24 in its unseated or open position and allow for venting of the crank case through the air outlet passages 20 and 13 in the counter-weight and shaft, respectively, and the outlet ports 17 in the block 12.

When the tool is held in its inverted position, that is, with the end journal lowermost, the drill bit 5 and the passage 20 will both point upward. In this position, the ball valve 24 will, when the drill is idle, automatically seat itself and close the vent by the force of gravity. When the tool, however, is operated in this inverted position, centrifugal forces which are set up by rotation of the crank shaft 9 will automatically unseat the valve and retain the latter in its unseated position against the stop 25 during the operation of the drill for venting of the crank case through the passages as before. Should the tool be stopped in this inverted position, the ball valve will close by gravity and prevent any lubricant leaking out of the case through the vent passages.

When the drill is held in a position with the drill bit 5 and crank shaft 9 horizontal, the end journal 10 will be likewise disposed, and the valve 24 will automatically seat by gravity should the crank shaft be stopped with the passage 20 above the axis of the shaft. Starting the drill with the crank shaft in this position, the valve 24 will be automatically unseated to open the vent by centrifugal forces set up on the rotation of the crank shaft. Should the crank shaft be stopped while the tool is held in this horizontal position with the passage 20 below the axis of the shaft, the ball valve will automatically unseat by gravity, and in starting the drill from this position, centrifugal forces set up on the rotation of the crank shaft will co-operate with gravity to hold the valve 24 open to vent the crank case.

Should the drill be held in any position at an angle, either up or down, to the several specified positions mentioned, the valve 24 will become automatically unseated either by gravity or centrifugal forces, depending on whether the passage 20 opens upward or downward, as will be apparent; centrifugal forces, however, playing an important part in either automatically unseating the valve or co-operating with gravity to retain the valve unseated during the operation of the tool should the crank shaft be started from a position with the valve initially opened by gravity.

The lubricant in the crank case is applied to the moving parts by a splash method. This has slow moving properties and, being heavier than air, is thrown from the venting opening 20 during the rotation of the crank shaft, so that none of it is carried out with the escaping air. The structure de-

scribed prevents an accumulation of air pressure in the case 1 from leaking of the compressed air into the case past the pistons and valves, without an opportunity afforded for the lubricant in the case finding its way out of the case with the escaping air. With the passages 20 inclined to the axis of the crank shaft, any lubricant finding its way into the same will be thrown back into the case by centrifugal force and not allowed to be carried out through the escaping air.

Fig. 3 shows that a plurality of passages 20 are provided in the counterweight 14, and thus a plurality of ball valves 24 therefor are used. This is done for the reason that the space within the tool is small and a large chamber or passage for the venting of accumulated air is out of the question. Sufficient area for this outlet passage is gained by a plurality of them, as described. The handle 3 is secured to the closure 12. The counterweight 14 has a tapered bore 14^a to fit a tapered part 9^a of the crank shaft 9 just inside of the closure block 12 and is keyed thereon, the keyway 14^b being shown in Fig. 3. A tension plate 26 is clamped between the parts on the crank case 1 and end block 12 and holds the outside bearing ring 11^a in place, as in said Hanssen application.

While we have shown and described herein in detail an air venting means constructed in accordance with our invention, it is of course to be understood that the details of structure and arrangement of parts may be variously changed and modified without departing from the spirit and scope of our invention.

We claim as our invention:

1. In a piston actuated pneumatic tool, the combination with a crank case, of a handle carrying block at one end of the case and having one or more air outlet ports, a crank shaft in said case and having an end journal supported by said block, a counter-weight in the case at said block and mounted on said shaft, said shaft and counter-weight having air outlet passages communicating with the exterior of the case and ports, respectively, and a valve carried by the counter-weight in the passage thereof for controlling the same, said valve being opened by centrifugal forces set up on rotating the crank shaft.

2. In a piston actuated pneumatic tool, the combination with a crank case, of a handle carrying block at one end of said case and having an interior vent chamber with outlet ports, a crank shaft in the case and having an end journal supported by said block, a counter-weight in the case at the block and mounted on the crank shaft, said end journal and counter-weight having air outlet passages communicating with the interior of the case and said chamber, respectively, a cup-shaped member fitting in said chamber over the end journal, a tube carried by said

member and extending into the passage in said end journal, and a valve carried by the counter-weight in the passage therein and being opened by centrifugal forces set up on rotating the crank shaft.

5 In testimony that we claim the foregoing as our invention, we affix our signatures, this 5th day of November, 1923.

AXEL LEVEDAHL.
REINHOLD A. NORLING.
